UNITED STATES PATENT OFFICE.

GREENBURY REED, OF GREENCASTLE, INDIANA.

IMPROVEMENT IN HARROWS.

Specification forming part of Letters Patent No. 128,067, dated June 18, 1872.

Specification describing a certain Improvement in Harrow, invented by GREENBURY REED, of Greencastle, in the county of Putnam and State of Indiana.

Figure 1 is a side view, partly in section, of a harrow illustrating my invention. Fig. 2 is a top view of the same.

My invention has for its object to improve the construction of harrows, so that the teeth can be conveniently cleared of rubbish when required; and it consists in the construction and combination of various parts, as herein-after more fully described.

A represents an ordinary harrow-frame, to which the teeth B are attached in the ordinary manner. The teeth B should be made a little longer than usual, so that they may pass through the clearer-frame C and still have sufficient working length. C is the clearer-frame, which is made in the same shape as the harrow-frame A, but lighter. The forward end of the frame C should be turned upward, or should have a short upwardly-curved draw-bar attached to it to guard against rubbish getting between the frames A and C. To the frame C are attached four, more or less, standards, D, which pass up through holes in the harrow-frame A, and upon the upwardly-projecting ends of which are placed coiled-wire springs E. The upper ends of the springs E are secured to the upper ends of the standards D, and their lower ends rest upon the upper sides of the bars of the harrow-frame A, so as to draw and hold the frame C close up against the frame A. To the frame C are attached standards F, which pass up through holes in

the frame A, and to the upper ends of which are pivoted the ends of a cross-bar or shaft, G. To the cross-bar or shaft G, near its ends, are attached levers H, the rear ends of which are connected by a cross-bar or round, I, which serves as a handle for operating the said levers. To the forward ends of the levers H are pivoted the upper ends of the connecting-rods or chains J, the lower ends of which are pivoted to the harrow-frame A.

By this construction, by operating the levers H, the frames A C are forced apart, forcing off any rubbish that may have caught upon the teeth B, clearing them perfectly from said rubbish. The frames A C are again drawn together as soon as the levers H are released by the action of the springs E.

I am aware that harrow-cleaners of a different construction and arrangement of parts have been used heretofore, and that a harrow has been lifted through another harrow-frame to avoid stones or other obstacles, but these form no part of my invention.

Having thus described my invention, I claim as new and desire to secure by Letters Patent—

The clearer-frame C, having standards D, with springs E, combined, as described, with harrow A, placed thereover, so as to enable said frame C to be held by springs against harrow, and to be moved down, for the purpose set forth.

GREENBURY REED.
